Primary Examiner—Celia Murphy(74) Attorney, Agent, or Firm—Marshall A. Lerner, Esq.; Finn T. Simmensen, Esq.; Kleinberg & Lerner, LLP(57) CLAIM

The ornamental design for a portion of a shoe bottom, as shown and described.

DESCRIPTION

FIG. 1 is a perspective view of a portion of a shoe bottom showing my new design;

FIG. 2 is a bottom plan view thereof; and,

FIG. 3 is a front elevational view thereof.

Broken lines in the figures are for illustrative purposes only and form no part of the claimed design.
